UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

TRANSITION CAR-COUPING.

1,309,290.

Specification of Letters Patent.

Patented July 8, 1919.

Application filed April 11, 1918. Serial No. 227,840.

To all whom it may concern:

Be it known that I, WILLIAM KELSO, a citizen of the United States, residing at Pittsburgh, in the county of Allegheny and State 5 of Pennsylvania, have invented certain new and useful Improvements in Transition Car-Couplings; and I do hereby declare the following to be a full, clear, and exact description of the invention, such as will enable 10 others skilled in the art to which it appertains to make and use the same.

My invention relates to the construction of transition car couplings designed to be used in equipping cars during the period when 15 car couplings of the European hook type are being gradually supplanted by couplers of the Master Car Builders type. The object of the invention is to produce a simple and effective transition coupling capable of not 20 only coupling with a similar coupling, but also with the European type of coupling and the M. C. B. type of coupler as well. A further object of the invention is to provide a transition car coupling which may 25 readily be converted into a typical M. C. B. coupler when the need for transition couplings no longer exists.

Generally stated, these objects of my invention are accomplished by pivotally 30 mounting a laterally swinging yoke on the outer end of the knuckle of an M. C. B. coupler, by movably mounting on the yoke a link member adapted to coöperate with the hook of a coupling of the European type, 35 and by pivotally mounting the yoke on the knuckle pin of the coupler through instrumentalities permitting the yoke to swing independently on the axis of its pivotal connection with the outer end of the knuckle.

40 In the drawings illustrating the best mode in which I have contemplated applying the principle of the invention, the scope whereof is pointed out in the claims,

Figure 1 is a plan view of a transition car 45 coupling embodying the invention.

Fig. 2 is a side elevation of the construction illustrated in Fig. 1.

Fig. 3 is a view of the construction showing 50 it in elevation as seen when looking in the direction of the arrow 3 in Fig. 1.

Fig. 4 is a detail view, partly in elevation and partly in vertical section, showing the auxiliary coupling members.

The transition car couplings involves a

coupler head 1, a knuckle 2 pivotally mounted thereon by means of a knuckle pin 3, and a lock 4 serving to restrain outward rotation of the knuckle to uncoupled position. These parts, which are elements common to the M. C. B. type of coupler, may be of any 55 suitable construction or of the well known form illustrated in the drawings.

At its outer end the knuckle 2 is formed with a vertically extending pivot pin opening adapted to receive a pivot pin 5 by 60 which a laterally swinging yoke 6 is attached to the knuckle. The yoke 6 embraces the outer end of the knuckle, extending above and below it, and is provided with vertically aligned pivot pin bosses 7 adapted 65 to receive the pivot pin 5 by which pulling strains are transmitted from the yoke to the knuckle. Between its top and bottom walls and parallel thereto the yoke is preferably 70 provided with vertically spaced studs or fingers 8 which extend rearwardly, terminating close to the forward face of the knuckle. These studs and the top and bottom arms of the yoke 6 form pockets or recesses 9 for 75 receiving a link member 10 that coöperates with the hook member of a coupling of the European type (not shown), the vertical height of the link 10 thus being capable of 80 adjustment as the height of the coupling on the adjoining car or other conditions may 85 dictate. The link 10 may slide rearwardly in the recesses 9 to allow for the movements of the cars as the buffers carried thereby move in and out; but the knuckle 2 prevents the link from escaping from any recess in 90 which it may be placed. In order to make the studs 8 as long as possible and yet allow the yoke 6 to have an extended swinging movement, the ends of the studs may be beveled, as indicated at 11, to afford proper clearance 95 between their ends and the forward face of the knuckle 2 during the swinging of the yoke toward the knuckle side of the coupler head.

Projecting horizontally from each of the 100 pivot pin bosses 7 of the yoke is a flange 12 having therein an arcuate slot 13 whose center is the pin 5 on which the yoke 6 rotates. The flanges 12 respectively extend into suitable horizontal slots 14 formed in collars 15 105 that are rotatably mounted on the knuckle pin 3. Rivets 16 passing through the flanges of the collars 15 and through the corre-

sponding arcuate slots 13 of the yoke form a jointed connection between the yoke 6 and collars 15 permitting the yoke to swing independently of the collars when the car 5 is passing around a curve. When not in use the devices for forming a coupling with a hook of the European type may be swung to the knuckle side of the coupler head 1 upon the knuckle pin 3 as a pivot, and the 10 pin 5 may be carried in the pivot pin opening in the outer end of the knuckle 2.

I claim:

1. In a transition car coupling, the combination with a coupler head, a knuckle pivotally mounted thereon and having a vertically extending pivot pin opening in its outer end, and a lock for said knuckle, of a yoke embracing the outer end of said knuckle, a pivot pin passing through said 15 yoke and the opening in the outer end of the knuckle, and a link member carried by said yoke and longitudinally slidable with respect thereto and adapted to be connected to a hook coupling of the European type.

2. In a transition car coupling, the combination with a coupler head, a knuckle pivotally mounted thereon, and a lock for said knuckle, of a yoke embracing and pivotally mounted upon the outer end of said knuckle, 20 means for pivotally connecting the yoke to the outer end of the knuckle so that said yoke may swing laterally, and means longitudinally slidable with respect to said yoke for connecting said yoke to a hook coupling 25 of the European type.

3. In a transition car coupling, the combination with a coupler head, a knuckle, a knuckle pin for pivotally mounting said knuckle upon said head, and a lock for said 30 knuckle, of a yoke, means carried by said yoke for connecting the latter to a hook coupling of the European type, means for pivotally connecting said yoke to the outer end of said knuckle, and means for pivotally 35 connecting the yoke to the coupler head through said knuckle pin.

4. In a transition car coupling, the combination with a coupler head, a knuckle piv-

otally mounted on said head, and a lock for 50 said knuckle, of a yoke pivotally mounted on the outer end of said knuckle, means carried by said yoke for connecting the latter to a hook coupling of the European type, and means pivotally connecting the yoke to the head so as to permit said yoke to be swung 55 on the axis of rotation of the knuckle.

5. In a transition car coupling, the combination with a coupler head, a knuckle pivotally mounted thereon, and a lock for said knuckle, of a yoke mounted on the outer end 60 of said knuckle, and a longitudinally slideable link device for connecting said yoke to a hook coupling of the European type, said yoke having a plurality of rearwardly opening recesses each adapted to receive said link 65 device and permit it to slide longitudinally therein, and said knuckle being adapted to prevent the escape of said link device from said recesses.

6. In a transition car coupling, the combination with a coupler head, a knuckle pivotally mounted thereon, and a lock for said knuckle, a yoke embracing the outer end of the knuckle and pivotally connected thereto and provided with a plurality of recesses 75 each adapted to receive a link member, and a link member adapted to be received by said recesses and to be connected to a hook coupling of the European type, said link member being adapted to slide longitudinally in 80 said recesses.

7. In a transition car coupling, the combination with a coupler head, of a knuckle, a knuckle pin for pivotally mounting the knuckle upon the head, a yoke embracing the outer end of the knuckle, means for pivotally connecting the yoke to the outer end of the knuckle, means for connecting the yoke to a hook coupling of the European type, and means for pivotally connecting the yoke to 85 the head at the knuckle pin, said last named means involving a member having a movable connection with the yoke whereby the latter 90 may swing independently.

In testimony whereof I affix my signature. 95
WILLIAM KELSO.
